UNITED STATES PATENT OFFICE.

RICHARD LOSSING, OF SOUTH PASADENA, CALIFORNIA, ASSIGNOR TO LOSSING MANUFACTURING COMPANY, OF LOS ANGELES, CALIFORNIA, A CORPORATION OF CALIFORNIA.

GASOLINE METER.

1,414,964.

Specification of Letters Patent.

Patented May 2, 1922.

Application filed November 27, 1920. Serial No. 426,828.

To all whom it may concern:

Be it known that I, RICHARD LOSSING, a subject of the King of Great Britain, residing at South Pasadena, in the county of Los Angeles and State of California, have invented new and useful Improvements in Gasoline Meters, of which the following is a specification.

It is the object of this invention to provide a meter particularly adapted for measuring the fuel consumption of an internal combustion engine. I have shown the invention as applied to the engine for a motor vehicle, and have described this particular embodiment of the invention, although it will be obvious that the meter may be readily employed wherever it is desired to measure the flow of a fluid.

It is the object of the invention to provide a meter which will accurately measure and register the fuel consumption of an internal combustion engine, the registering mechanism being conveniently positioned upon the instrument board of the motor vehicle, and including a trip registering mechanism as well as a total registering mechanism.

The invention will be readily understood from the following description of the accompanying drawings, in which:

Figure 1 is a side elevation of a portion of an automobile showing the engine thereof provided with the improved meter for measuring the fuel consumption.

Fig. 2 is a front elevation of a portion of the instrument board of the automobile showing the registering mechanism of the meter.

Fig. 3 is a vertical section through the registering mechanism taken on the line 3—3 of Fig. 2.

Fig. 4 is a transverse section on the line 4—4 of Fig. 3.

Fig. 5 is a detail section on the line 5—5 of Fig. 4.

Fig. 6 is a horizontal section on the line 6—6 of Fig. 4.

Fig. 7 is a transverse section on the line 7—7 of Fig. 3.

Fig. 8 is a longitudinal section on the line 8—8 of Fig. 3.

Fig. 9 is a plan view of the measuring mechanism.

Fig. 10 is a longitudinal section through the same on the line 10—10 of Fig. 9.

Fig. 11 is a transverse section on the line 11—11 of Fig. 10.

Fig. 12 is a detail section on the line 12—12 of Fig. 11.

Figs. 13 and 14 are transverse sections on the lines 13—13 and 14—14 of Fig. 10. 60

Fig. 15 is a detail section on the line 15—15 of Fig. 10.

Fig. 16 is a detail section on the line 16—16 of Fig. 11.

Fig. 17 is a transverse section on the line 17—17 of Fig. 3.

Fig. 18 is a transverse section on the line 18—18 of Fig. 10.

In the drawings I have shown an automobile 1 including instrument board 2. The 70 engine of the automobile is shown at 3 provided with a carburetor 4, and the usual vacuum feed tank 5 for the fuel. The measuring device 6 is positioned in the supply pipe 8 leading from tank 5 to the carburetor, and the measuring mechanism actuates the registering mechanism 7 mounted upon instrument board 2. While I have shown the measuring mechanism in a supply pipe leading from a vacuum tank, it will be obvious that the device may be as readily employed in a supply pipe to which the fuel is supplied by any system other than a vacuum feed. 80

The measuring device in supply pipe 8 85 includes a reciprocating piston adapted to supply measured charges of fuel to the carburetor, the reciprocation of the piston actuating an oscillating member which in turn actuates the registering mechanism. The 90 measuring piston is reciprocated by the suction through the intake manifold of the engine.

The specific construction of the measuring mechanism includes a tank 10 closed at its 95 respective ends, and having a transverse partition 11 forming an actuating cylinder 12 and a measuring cylinder 13. The top of the tank is divided from the actuating cylinder by a transverse partition 14 form- 100

ing a space 15 adapted to receive the mechanism for translating the reciprocatory movement of the measuring device into oscillatory movement of a flexible connection 5 leading to the registering mechanism.

A reciprocating rod 16 extends axially through the measuring tank and projects into space 15 at its upper end, and is received in a bore 17 formed in the base 18 10 of the tank at its lower end.

A piston 19 is slidably received upon rod 16 within cylinder 12, and a similar piston 20 is slidably mounted upon the rod within cylinder 13. These pistons are connected 15 by rods 21, so that reciprocating of actuating piston 19 will cause similar movement of measuring piston 20. The piston 20 as it approaches the lower limit of its movement will abut against a lug 22 upon rod 16 for 20 initiating movement of the rod 16 downwardly so that said movement of the rod will complete the downward movement of the piston. A similar lug 23 upon rod 16 is engaged by piston 20 as it subsequently 25 approaches its upper limit of movement for initiating the return movement of the rod 16 to its first position so as to cause the completion of the cycle of movement of the piston. After the movement of rod 16 in 30 opposite directions has been started as thus described, its movement will be completed through a suitable actuating spring as hereinafter described.

The partition 11 is provided with a transverse bore 24 which traverses the axis of the measuring tank, so that rod 16 extends across said bore. At one end this bore terminates in a nipple 25 to which is connected supply pipe 8 leading from vacuum tank 5, 40 and the other end of the bore beyond rod 16 communicates with a bore 30 extending through partition 11 to cylinder 13 above piston 20. The bore 24 before crossing the axis of the tank communicates with a bore 45 leading around the axis of the tank to the opposite side of partition 11 where it communicates with a pipe 26 extending from partition 11 to base 18. The pipe 26 communicates with a bore within base 18 which 50 terminates in a transverse bore 27 communicating with bore 17. A bore 28 extends from the bore 17 at the level of bore 27 and at an angle thereto, and this bore communicates with the cylinder 13 below piston 20. 55 The fuel discharge from cylinder 13 is provided for by a bore 31 in partition 11 extending from bore 30 to the exterior of the partition where it terminates in a nipple 32. The supply pipe 8 leading to the carburetor is connected to this nipple so that the fuel supplied to the measuring tank through nipple 25 and measured by the reciprocation of piston 20 is then supplied through nipple 32 to the engine. The space 60 within cylinder 13 below piston 20 com-

municates with a transverse bore 33 in the base 18, and this latter bore is connected by a pipe 34 with the bore 31 adjacent its discharge nipple.

It will be noted that both the bores 31 and 70 33 traverse the axis of the measuring tank as does also the bore 24, and the reciprocating rod 16 arranged in the axis of the tank is adapted to shut off and open these bores through its reciprocatory movement. 75 For this purpose the rod is provided with an annular groove 35 adapted to aline with either bore 24 or bore 31 when the rod is moved to its respective limits of movement, and at its lower end the rod is provided 80 with a similar annular groove 36 adapted to aline either with bore 33, or with the bores 27 and 28. The parts are so arranged that when the annular grooves are out of alinement with the bores, the latter are 85 closed by rod 16, but when the annular grooves are alined with the bores, the latter are open for the passage of fuel.

In the upper portion of partition 11 is arranged a transverse bore 40 extending 90 across the axis of the tank and terminating in a nipple 41 projecting from the tank. This nipple is connected by a conduit 42 with the intake manifold 43 of engine 3, so that when the engine is running a suction 95 is created through the conduit 42. The bore 40 communicates with cylinder 12 beyond the axis of the tank as by the bore 44, and adjacent nipple 41 the bore 40 also communicates with a pipe 45 extending upwardly to the partition 14. This partition is provided with the transverse bore 46 leading from pipe 45 and extending beyond the axis of the tank where it communicates with cylinder 12 above piston 19 as by the bore 47. 100

A bore 48 is also arranged in partition 11 so as to communicate with the atmosphere and extend across the axis of the tank beyond which it leads to bore 44. In similar manner a bore 49 is arranged in partition 110 14 so as to communicate with the atmosphere and extend across the axis of the tank. Beyond said axis this bore leads into the bore 47.

The rod 16 is adapted to close bores 40, 115 46, 48 and 49 in the manner previously described, and the rod is provided with an annular groove 50 adapted to aline with either bore 49 or 46 as the rod is reciprocated, and is also provided with an annular groove 51 120 adapted to aline with either bore 40 or 48. By this arrangement bores 49 and 46 are alternately opened and closed and bores 40 and 48 are also alternately opened and closed as rod 16 reciprocates.

The operation of the measuring device as thus described is as follows:

At the beginning of a cycle of operation rod 16 is at its upper limit of movement as shown in Fig. 10, and bores 49, 40, 24 and 130

33 are opened by the cooperating annular grooves of rod 16, while the rod closes bores 46, 48, 31 and 27. The engine being started a suction is created through bore 40 so as 5 to create a partial vacuum in cylinder 12 below piston 19, and air entering the cylinder above the piston through bore 49 will cause the piston to be forced downwardly within cylinder 12. This will cause a corresponding downward movement of piston 20, and as a consequence, fuel will be sucked into cylinder 13 above piston 20 through the intake bore 24 and bore 30. When piston 20 reaches lug 22, rod 16 will be started 10 downward and its actuating means to be described will complete the movement of the rod and of the piston, and as a consequence the annular grooves of rod 16 will be moved out of alignment with the respective bores 15 for closing the latter, and will be moved into alignment with bores 46, 48, 31 and 27 for opening the same. With the parts in this position piston 20 will have reached its lower limit of movement and a measured charge 20 of fuel will have been sucked into cylinder 13 above piston 20.

The suction through nipple 41 is now communicated through pipe 45, bore 46 and bore 47 to the cylinder 12 above piston 19, 25 and at the same time air at atmospheric pressure is admitted to cylinder 12 below piston 19 through bores 48 and 33. As a consequence pistons 19 and 20 will be moved upwardly. The fuel charge within cylinder 30 35 13 above piston 20 will be forced outwardly through bores 30 and 31 to the fuel supply pipe leading to the carburetor of the engine, and at the same time a fuel charge will be sucked into cylinder 13 below piston 20 through bores 24 and 24^a, pipe 26, and bores 40 45 27 and 28. As the piston 20 approaches its upper limit of movement, it will engage lug 23 for reversely moving rod 16 and as soon as such movement is started the actuating means for the rod will complete the movement 50 55 of the rod and piston. When the piston has completed its stroke the measured fuel charge above the piston will have been completely discharged to supply pipe 8 leading to the carburetor, while a new measured charge will have been sucked into cylinder 13 below piston 20. The cycle of operation is now repeated, the measured charge below the piston being discharged through bore 55 60 65 33, and pipe 34 to the discharge nipple 32, so that the charge will be supplied to the carburetor.

It will thus be seen that at each reciprocation of rod 16, measured charges of fuel 60 will be supplied to the carburetor, and by counting the reciprocations of the rod through suitable registering mechanism, graduated in accordance with the volume of fuel contained in each of the measured 65 charges, the amount of fuel supplied to the

carburetor may be accurately measured. The registering mechanism is actuated through the oscillations of a flexible connection which is turned in opposite directions each time the rod 16 moves up and down. 70

As an instance of this arrangement rod 16 is projected upwardly into space 15 and is provided with an annular groove 54, and a forked arm 55 is positioned with its prongs received at opposite sides of the rod in the 75 groove 54. The opposite end of arm 55 is pivoted in a notch 56 formed in a nipple 57 extending outwardly from the wall of the measuring tank. The pivotal mounting for the arm is so arranged that the reciprocation of rod 16 will swing the arm up and down, and the latter is provided with actuating means for completing the reciprocation of the rod when once started. For this purpose a slot 58 is provided in arm 55, and 80 a coil spring 59 is arranged in this slot with one end connected to the arm and the other end extending within nipple 57 and connected to the end wall of the same. When the arm is first moved upon its pivot 85 through the movement of rod 16, the spring will be moved to one side or the other of said pivot and will thus urge the completion of the swing of the arm for completing the movement of rod 16. 90

One of the prongs of arm 55 is elongated as shown at 60 and engages an arm 61 by being received between lugs 62 upon this latter arm. The arm 61 is fixed upon a shaft 63 journaled in the casing of the 100 measuring tank, so that movement of arm 55 will oscillate arm 61 and thereby oscillate the shaft 63. A flexible connection shown as a wire 64 is received through the bore of shaft 63 and is fixed therein against 105 movement relative to the shaft by a pin 65. The wire 64 is thus arranged for oscillation with shaft 63, and said wire extends to the registering mechanism mounted upon the instrument board of the automobile for actuating 110 the same. The wire may be enclosed within a flexible casing 66 as clearly shown in Figs. 3 and 11. It will be understood that this wire must be of suitable size, and of sufficient rigidity relative to its length, as 115 to cause said wire to oscillate, and not merely to twist.

The registering mechanism actuated by wire 64 comprises a trip registering mechanism adapted to be reset to zero after a trip 120 and a total registering mechanism.

The registering device is housed within casing 70 closed at its front end by the removable end cap 71. This end cap is provided with an axial opening 72 and with a display 125 opening 73 in the upper portion of the same, and a display opening 74 in its lower portion. Side walls 75 extend within casing 70 from the end cap, said side walls being mounted upon the end cap by means of lugs 130

76 received through suitable openings there-in. These side walls are connected by a rear plate 77, and a bearing 78 is supported by the end wall 77, and the cap 71 with the 5 end of said bearing projecting beyond cap 71 and carrying a disc 79 which overlies a portion of the end cap. This disc is cut away as shown at 80 in alinement with opening 74 and is also cut away as shown at 81 10 in alinement with opening 73. A transparent plate 82 may be received between discs 79 and the end cap.

The bearing 78 may be held in position by means of a nut 83 threaded upon the 15 rear end of the same against end wall 77, and a shaft 84 is journaled in this bearing with the end thereof projecting beyond disc 79 provided with a knurled head 85. Shaft 84 projects rearwardly beyond its bearing 20 78 and a gear wheel 86 is loosely mounted upon the same. A clutch disc 87 is fixed upon shaft 84 beyond the gear 86 as by the cotter pin 88, and leaf springs 89 are interposed between the friction disc and the gear 25 to cause a frictional driving engagement between the gear and shaft. It will be noted that this arrangement also permits of turning of the shaft by grasping its knurled head without causing similar rotation of gear 86. 30 A disc 90 is mounted upon the rear end of shaft 84 and is provided with lips 91 received in longitudinal grooves 92 formed in said shaft. The disc is also provided with cut out lips 93 bent downwardly over a collar 35 94 received upon shaft 84 between friction disc 87 and the disc 90.

The sleeve 94 is provided with an annular groove 95 adapted to receive prongs 96 of a plate 97 which is pivoted between arms 98 40 extending rearwardly from the respective side wall 75. A spring 99 is interposed between wall 77 and the plate 97 in order to yieldably swing the same toward the rear of casing 70. The longitudinal movement 45 of disc 90 and sleeve 94 along shaft 84 is adapted to swing plate 97 in the opposite direction for actuating the registering mechanism.

The disc 90 is provided with radially extending arms 101 to the outer ends of which are connected arms 102 extending toward the front end of the casing 70. At its forward end an annular ring 103 is fixed to arms 102, and this ring is in alinement with 55 opening 73. The ring is suitably graduated, so that when disc 90 is rotated and the arms 102 and ring 103 are similarly rotated, successive numbers will appear beneath the opening 73.

Disc 90 is adapted to be moved along shaft 84 by means of an axially disposed head 105 abutting against the disc and projecting outwardly through the rear wall 106 of the register casing. The rear end of this head is 65 provided with a transverse groove 107 adapt-

ed to receive a wedge-shaped head 108 which is journaled in a suitable bearing 109 projecting from the register casing. This head is suitably held against longitudinal displacement and is connected to the end of 70 wire 64 so as to be oscillated by the same.

The oscillations of the wedge-shaped head 108 will cause reciprocatory movement of head 105 through the engagement of the head within groove 107, and this movement of 75 head 105 will move disc 90 and sleeve 94 inwardly along shaft 84 so as to swing plate 97 on its pivot. After inward movement of the parts they are returned to their first position by spring 99 as soon as head 108 is 80 oscillated in the opposite direction. This swinging movement of plate 97 actuates an arm 110 adapted to engage a ratchet wheel 111 mounted upon a shaft 112 journaled in side walls 75. Arm 110 engages the ratchet 85 wheel for moving the same as plate 97 swings in one direction. During the reverse sliding movement of arm 110 the ratchet wheel is held against reverse rotation by means of a spring arm 114. The intermittent rotation 90 of shaft 112 as thus accomplished is adapted to rotate gear 86 for which purpose a worm 115 is provided upon shaft 112 and meshing with said gear.

A pinion 116 is also fixed upon shaft 112, 95 and through intermediate gear 117 drives the shaft 118 of any suitable total registering mechanism mounted in a casing 119 between side walls 75 and adapted to be displayed through the opening 76 in end cap 71, and the 100 alined opening 80 in disc 79.

The operation of the registering mechanism is as follows, it being understood that the graduations of band 103, and the total registering mechanism contained within casing 119 are so arranged with relation to the actuating mechanism for the same included as a part of the register and with relation to the measuring mechanism previously described, that the oscillations of wire 64 responsive to discharging of measured volumes of fuel to the engine will so rotate band 103 as to display through its opening in disc 79 the fuel consumption during a trip in a pre-determined unit such as gallons, and will 115 actuate the total registering mechanism so as to display the total fuel consumption in the same unit.

When plate 97 is swung upon its pivots as previously described, ratchet wheel 111 is 120 turned through arm 110, and as a consequence gear 86 is rotated through worm 115. The gear in turn rotates friction disc 87 which being fixed to shaft 84 will rotate the latter. Disc 90 being fixed for 125 rotation with shaft 84 by means of lips 91 received in grooves 92, said disc and arms 101 will be rotated so as to turn arms 102 and the graduated band 103. The trip registering mechanism is thus actuated and at the 130

end of a trip the graduated band 103 may be reset at zero by turning shaft 84 through its knurled head 85.

At the same time that the trip registering mechanism is being actuated as thus described, the rotation of shaft 112 will actuate the total registering mechanism through the train of gearing connecting the shaft of said registering mechanism and the shaft 112.

10 It will thus be seen that I have provided a device, wherein the fuel supply to an engine may be accurately measured, the movement of the measuring mechanism controlling a registering device which is provided 15 with a trip register adapted to be reset to zero and with a total registering mechanism.

While the construction of the measuring mechanism as above set forth provides for actuation of the measuring piston through 20 the suction in the intake manifold of the engine, it will be apparent that when the device is employed in connection with an engine having a pressure feed for the fuel, it will not be necessary to positively actuate the 25 measuring piston by suction as above set forth, since when such a system is employed the pressure of the fuel against opposite faces of the measuring piston will be sufficient to actuate said piston.

30 Under these circumstances the measuring tank may be made without a working cylinder 12, the space 15 being arranged directly above the measuring cylinder 13 with the bores for the measuring cylinder arranged in the partition between the cylinder and space 15 as previously described. The fuel entering through intake 25 will act against the respective faces of piston 20 so as to move the same and reciprocate rod 16 35 as previously described, and the movement of the rod will control the measuring means as hereinbefore set forth.

Various changes may be made without departing from the spirit of the invention as 40 claimed.

45 What is claimed is:

1. The combination with a liquid supply of measuring means, registering mechanism, and a rotatable flexible connection between 50 said measuring means and said registering mechanism.

2. A measuring tank having a reciprocating pump head adapted to draw in liquid from a source of supply and then discharge 55 said liquid to a point of consumption, a reciprocating rod, and cooperating means arranged so that movement of said pump head will initiate movement of said rod, spring

means for completing the movement of said rod, and registering mechanism actuated by 60 the movement of said rod.

3. A measuring tank having a reciprocating pump head adapted to draw liquid from a source of supply and then discharge said liquid to a point of consumption, a reciprocating rod actuated by the movement of said pump head, said rod and pump head having 65 cooperating valvular means arranged to cause functioning of said liquid inlet and discharge, and registering mechanism actuated by the movement of said reciprocating rod.

4. A measuring tank having a reciprocating piston actuated by suction against the respective faces of said piston, a reciprocating pump head actuated by said piston and adapted to draw in liquid from a source of supply and then discharge said liquid to a 75 point of consumption, and registering mechanism actuated by the movement of said 80 pump head.

5. A measuring tank having a reciprocating piston actuated by suction against the respective faces of said piston, a reciprocating pump head actuated by said piston and 85 adapted to draw liquid from a source of supply and then discharge said liquid to a point of consumption, a member actuated by the movement of said pump head to cause 90 functioning of said liquid inlet and discharge and to cause said suction to be alternately employed against the piston faces, and registering mechanism actuated by the movement of said member.

6. The combination with a liquid supply 95 of measuring means adapted to reciprocate an operating member, registering mechanism, a rotatable member adapted to actuate the same, and a rotatable flexible connection between said reciprocating member 100 and said rotatable member.

7. The combination with liquid measuring means, of registering mechanism including a main shaft adapted to be axially shifted by said measuring means, a rotatable member 105 loosely mounted upon the main shaft, a friction clutch fixed upon the main shaft, means for rotating said rotatable member through the axial movement of the main shaft, said movement engaging said friction clutch with 110 said rotatable member to rotate said shaft, and counting mechanism actuated by said shaft.

In testimony whereof I have signed my name to this specification.

RICHARD LOSSING.
